UNITED STATES PATENT OFFICE.

LIONEL W. CROMPTON AND EARLE N. OLIVER, OF TAMPA, FLORIDA.

OUTLET BOX OR FIXTURE.

1,255,863.

Specification of Letters Patent.

Patented Feb. 12, 1918.

Application filed May 1, 1915. Serial No. 25,202.

To all whom it may concern:

Be it known that we, LIONEL W. CROMPTON and EARLE N. OLIVER, citizens of the United States, residing at Tampa, in the county of Hillsboro and State of Florida, have invented certain new and useful Improvements in Outlet Boxes or Fixtures, of which the following is a specification.

Our invention relates to electric wiring fixtures, and more particularly to a new and improved outlet box or fixture for use in the walls or ceilings of a building or dwelling.

The primary object of our invention is to provide an outlet fixture for facilitating the connection and support of electric conductors or for supporting a chandelier or the like.

Another object of our invention is to provide an improved outlet fixture having means associated therewith for holding the electric conductors in fixed position to prevent dislodgment or short circuiting of the wiring system.

A further object of our invention is to provide an improved wiring fixture which is adapted for use in connection with that system of wiring known as the loop system, wherein a plurality of electric lamps or branch circuits are connected in multiple on a single line, it being necessary in the devices as at present used to scrape the insulation from the looped conductors and permanently attach branch wires or conductors thereto, this not only presenting a rather unneat appearance when exposed but also rendering the system easily susceptible to short circuit or the like.

A still further object of our invention is to provide a fixture having means associated therewith whereby the branch conductors may be detachably connected with the main conductors, also supporting, clamping, insulating and protecting members being provided and associated in a manner more fully described hereinafter.

With the above and other objects in view our invention resides preferably in the construction, combination, and arrangement of parts as hereinafter set forth in the specification and illustrated in the accompanying drawings, in which—

Figure 1 is a vertical sectional view through the floor and ceiling of a building showing one application of our improved outlet fixture.

Fig. 2 is a vertical sectional view of the fixture in position.

Fig. 3 is a bottom plan view of the embodiment of our invention showing the protecting cap removed.

Fig. 4 is a transverse sectional view of our improved fixture taken on the line 4—4 of Fig. 2 looking in the direction of the arrows.

Fig. 5 is a plan view of the protecting cap of the preferred form of our invention.

Fig. 6 is a plan view of the wire holding member.

Fig. 7 is a plan view of one of the clamping plates.

Fig. 8 is a side elevation of a modified form of our invention showing the same applied to a ceiling, the ceiling being in section.

Fig. 9 is a fragmentary vertical sectional view of one of the fastening members of our invention.

Similar reference characters indicate similar parts throughout the various views of the drawings.

Referring more particularly to the drawings in which the preferred embodiment of our invention is illustrated, the floor of a dwelling is designated 1 and the ceiling 2, the ceiling 2 being of any of the prevalent forms, our invention being applicable for use with any of the common forms of ceilings or walls. The stringers or rafters of the dwelling are designated 3 and 4. It is to be understood that while our invention is shown as applied to a ceiling the scope of its uses is not necessarily limited to that shown.

The preferred embodiment of our invention comprises a relatively short conduit 5 the opposite extremities thereof threaded externally as indicated at 6 and 7, the lower extremity projecting through an aperture 8 formed in the ceiling 2, said aperture 8 being slightly larger in diameter than the conduit 5. A clamping plate 9 having a centrally threaded aperture 10 is disposed upon the threaded extremity 7 of the conduit 5 as shown to advantage in Fig. 2 said clamping plate being disposed on the inner face of the ceiling 2 for a purpose which will hereinafter appear.

A second clamping plate is provided and comprises a disk-like member 11 having a laterally extending annular flange 12 on its periphery. The clamping plate 11 is pro-

vided with a plurality of apertures 13 for a purpose which will hereinafter appear, said clamping plate also being provided with a centrally located aperture 14 adjacent which 5 is formed a laterally extending annular flange 15, said flange being internally threaded for engagement, as at 16, with the threaded extremity 7 of the conduit 5. It will be noted that the outside diameter of the flange 10 15 is such that the same will be snugly received in the aperture 8 to prevent dust, dirt or moisture from passing therearound. It will be readily observed that in supporting the conduit 5 in position the plate 9 will 15 first be disposed as shown and then the plate 11 threaded into position, clamping the ceiling or the like 2 between the annular flange 12 and the plate 9 in the manner shown.

The structure above described may be 20 formed of any suitable material and need not be formed of insulating material. However, the structure hereinafter described is 25 preferably formed of insulating material and includes means to support the electric conductors within the conduit 5 as well as means for facilitating connection of the conduits with a branch circuit, and a protecting and insulating cap therefor.

The clamping plate 11 is provided at any 30 suitable point or points with a plurality of apertures designated 17 shown to advantage in Fig. 9. An insulating connector plate is provided and is designated 18, the plate 18 being preferably formed of a resilient material such as hard rubber, porcelain, or the like. The plate 18 is provided on its inner face with a plurality of projections 19 adapted for snug engagement in the apertures 17 of the plate 11, there preferably being 35 as many projections 19 as there are apertures 17 so that a snug non-rattling engagement may be made between the plates. Each of the projections 19 is provided with a concentrically arranged aperture extending vertically therethrough and through the plate 18 and being designated 20. A protecting cap is provided and comprises a disklike element 21 preferably formed of insulating material and having a laterally extending 40 annular flange 22 formed on the periphery thereof, the inner face 23 being preferably in spaced relation to the plate 18 for a purpose which will hereinafter appear. The cap 21 is provided with a centrally located 45 aperture 24 for a purpose which will hereinafter appear. Bolts or the like fastening means 25 are disposed in suitable openings 26 formed in the cap 21 and extend through the apertures 20, said bolts 25 having nuts 50 55 60 65 27 on their inner extremities, said nuts bearing upon clamping washers 28 preferably formed of insulating material, all for the purpose of retaining the clamping plate 11, the insulating connector plate 18, and the protecting cap 21 in snug engagement.

The clamping plate 11 and the insulating connector plate 18 are further complementally apertured adjacent their respective peripheries to receive retaining screws or the like 29, the cap 21 being recessed as at 30 70 at the points over the retaining screws 29 so as to facilitate driving of the screws after the clamping plate, connector plate, and cap have been secured together. The insulating connector plate 18 is provided with a central aperture 31, said aperture 31 being preferably tapering in form as shown, the inside diameter thereof being slightly smaller than the inside diameter of the conduit 5 for a purpose which will hereinafter appear. 75 Connecting lugs 32 and 33 are carried by the insulating connector plate 18 and are substantially Y-shaped in configuration having a plurality of connecting screws or the like associated therewith. The connecting 80 lugs 32 and 33 are secured to the connector plate 18 by means of screws or the like 34 and 35 respectively. The lug 32 is provided with a pair of connecting screws or the like 36 and 37. The connecting lug 33 is likewise 85 provided with a pair of connecting screws or the like 38 and 39. The main conductors of the wiring system are designated 40 and are looped as indicated at 41 and 42, the looped portions thereof being free of insulating 90 material and connected with the screws 37 and 38. The branch conductors 43 are connected to the screws 36 and 39 and are disposed through the aperture 24 in the cap 21 and in actual practice would preferably take 95 the form of the usual flexible cord conductor designated 44 in Fig. 1, this form of our invention being particularly adapted for use in connection with drop lights and the like.

In order to prevent undue lateral movement of the conduit 5 we provide a strap 45 internally threaded for engagement with the threaded extremity 6 of the conduit 5 and provided with a plurality of radially extending apertured lugs 46, to which are secured guy wires 47 or similar retaining means, said guy wires being secured at 48 to the rafters 3 and 4. The usual knob insulators are shown and designated 49 for supporting the conductors 40. 105 110 115

In order to prevent undue movement of the conductors 40 in the conduit 5 we provide a clamping means which comprises a pair of disklike members 50 and 51. An internally threaded annularly flanged collar 120 52 is mounted upon the threaded extremity 6 of the conduit 5 and is bolted or otherwise secured as indicated at 53 to the dielectric disk-like elements 50 and 51. One of the disk-like elements, or wire holder, 51, is provided with a central aperture 54, the upper face of said disk 51 having a plurality of radially extending grooves or the like 55 adapted for reception of the conductors 40. In assembling the device the flanged collar 125 130

52 is threaded onto the conduit 5 and the wire holder 51 is disposed thereon. The conductors 40 are now placed in such of the grooves as may be convenient and the disk 50 is bolted into position, clamping the conductors between the same and the wire holder 51. It will thus be seen that undue movement of the conductors is prevented, as well as ingress of moisture, dust, vermin and 10 the like.

The purpose of the apertures 13 will readily be appreciated from an inspection of Figs. 2 and 4, it being noted that the liability of short circuit owing to contact of the plate 15 11 with the connector screws is thereby obviated.

Attention is called to the fact that should it be desired the conductors 40 when looped within the conduit 5 may be stretched taut. 20 To prevent contact of the conductors with the inner surface of the conduit 5, the tapered opening 31 has been provided as hereinbefore described.

In Fig. 8 we have illustrated a modified 25 form of our invention. It is well known to those skilled in the art that in the use of outlet fixtures for chandeliers, piping, and the like, it is necessary that a supporting bracket, commonly known as a "crow's foot," 30 is employed. We have illustrated in Fig. 8 a structure of this type embodying a head 56, and radially extending arcuate legs 57 having base portions 58 formed in the usual manner. There are preferably three of 35 these provided substantially at angles of 120° apart. The base portions 58 are adapted for engagement, by means of bolts or the like 59 with the insulating connector and clamping plates 18 and 11. The supporting conduit of the usual form of depending light structure is designated 60 and is threaded into the head 56. The branch conductors are designated 61. In practical use, it is, of course, understood that 45 the usual protecting canopy may be provided for presenting a pleasing appearance to the fixture as well as preventing access to the interior.

From the above description taken in connection with the accompanying drawings it 50 is thought that a clear and comprehensive understanding of the construction, uses, and advantages of our invention may be readily gathered. It will be noted that the form 55 of the invention illustrated in Fig. 2 is not in the least changed in the modification illustrated in Fig. 8, this merely serving to illustrate the flexibility of application of the device to various uses, it being noted that we 60 are not limited to the exact form of protecting casing for supporting an attaching means, and that the device need not be utilized for electric light fixtures but may

be, by enlargement, adapted for use in connection with devices requiring larger power, 65 such as electric motors and the like.

While we have shown and described our invention as possessing a peculiar form and construction, it is desired that it be understood that we may make such changes in 70 the details thereof as do not depart from the spirit and scope of the invention as claimed.

Having thus described our invention what we claim and desire to secure by Letters 75 Patent is:

1. The combination with the ceiling and rafters, of an outlet box including a conduit with means for clamping the conduit to the ceiling, guys between the conduit and the rafters for steadyng the conduit, connecting lugs in the outlet box for receiving the looped ends of the line wires, and clamping means on the conduit for holding the looped ends taut. 80

2. An outlet box including a conduit with a pair of clamp plates at one end for securing the conduit to a ceiling, connecting means for connecting the looped ends of wires in the conduit, a cap for the outlet 90 box with openings for access to the connecting means, and combined covering means for the end of the conduit and clamping means for the wire ends, at the other end of the conduit. 95

3. The combination of the conduit with a clamp plate having openings, a dielectric connector plate superposed on the clamp plate over the openings and having an inwardly curved flange with an offset from 100 the inner wall of the conduit, connector lugs recessed in the connector plate by fastening means adjacent to the clamp plate openings, and looped wire ends adapted to be secured to the connector lugs, the offset of the inwardly curved flange preventing contact of the wires with the conduit. 105

4. In an outlet box, the combination with the conduit, a grooved wire holder on the end of the conduit, and a disk for covering 110 the grooves and clamping wires in place in the grooves.

5. In an outlet box, the combination with the conduit, of a flanged collar on the end of the conduit, an apertured wire holder 115 with radial wire grooves leading from the aperture, a disk for covering the grooves, and means for clamping the wire holder and disk on the flanged collar.

In testimony whereof we affix our signatures in presence of two witnesses.

LIONEL W. CROMPTON.
EARLE N. OLIVER.
